UNITED STATES PATENT OFFICE.

HERMAN B. SEELY, OF CHICAGO, ILLINOIS.

FIREPROOF FLOORING.

SPECIFICATION forming part of Letters Patent No. 540,692, dated June 11, 1895.

Application filed June 11, 1894. Serial No. 514,186. (No model.)

To all whom it may concern:

Be it known that I, HERMAN B. SEELY, a citizen of the United States of America, residing at Chicago, in the county of Cook and State 5 of Illinois, have invented certain new and useful Improvements in Fireproof Floorings, of which the following is a specification.

My invention relates to improvements in fire proof floorings, its object being to provide 10 a cheap, light and effective flooring practically proof against fire, water and smoke and so simple as to require no skilled labor in its construction.

The invention is fully described and explained in this specification and shown in the accompanying drawings, in which—

Figure 1 is a vertical section of a flooring embodying my improvements, the plane of section being at right angles to the flooring-beams and a suitably-suspended ceiling being shown in operative connection with the flooring. Fig. 2 is a vertical section of the flooring and ceiling, the plane of section being parallel to the beams. Fig. 3 is a perspective view 25 of one of the corrugated metal sheets forming a part of the flooring. Fig. 4 is an enlarged vertical section similar to Fig. 2, illustrating the connection of the meeting edges of two corrugated metal sheets and the relation of 30 the flooring-strips and ceiling-hangers thereto. Fig. 5 is a view, partly in vertical section and partly in side elevation, showing the relation of the ceiling-hangers to the beams; and Fig. 6 is an elevation of the ceiling-hanger, 35 the view being in the direction indicated by the arrow in Fig. 5.

In the views, A, A are parallel metal beams of ordinary construction adapted to support a floor and ceiling and B, B are corrugated 40 metal sheets of suitable dimensions resting upon and transverse to the beams and having at their meeting edges vertical flanges, b, b, preferably covered and held in contact by caps, C.

The flanges, b, b, and cap, C, of each joint are inclosed in and covered by a longitudinal 45 groove, d, in the lower edge of a suitable flooring strip, D, the margins, d', d', of the members on either side the groove being shaped 50 as shown in Fig. 4 to conform substantially to the adjacent gutters in the corrugated sheets, the bearing lines of the flooring strips being

coincident with the bearing lines of the corrugations upon the beams. Nails, E, E, passing transversely through the flooring strips, 55 D, the caps, C, and flanges, b, b, bind all the parts together, so that each of the vertical elements contributes to the strength of the entire structure.

The ordinary flooring, F, is nailed transversely upon the flooring strips, D, and the space between the corrugated sheets and the flooring boards may be packed with mineral wool, cement, or other suitable non-conducting material. The corrugated sheets have 65 great strength in proportion to their weight and in this use have the special advantage of providing uninterrupted and practically contiguous air-ducts across the beams and the flooring thus constructed is light, stiff, cheap 70 and easily applied and is substantially proof against fire, water, or smoke. In order, however, to guard against any possible leakage, I prefer to provide suitably inclined drainage troughs, T, transverse to the corrugations of 75 the strips, and immediately under the lines of juncture of the ends of the sheets. The ends of the sheets are overlapped and riveted, as shown in Fig. 1, and the extreme end of each gutter of the underlying edge is preferably bent downward as at b', b', Fig. 3, to 80 form a drip spout. Any water passing through the floor, F, and the packing material beneath it must pass along the corrugated sheets and drop from the drip spouts, b', b', into the 85 corresponding drainage troughs, T, T, beneath and thus be carried to suitable points of escape.

The flooring thus described may evidently be used in combination with a ceiling suspended and constructed in any desired manner, but it is particularly adapted to the use of the simple and effective ceiling hanger illustrated in the drawings, in which, G, G' are the two members of an angle iron having 95 a plane upper end, a portion of the member, G, being left in the plane of the member, G', to form a hook or bracket, g, as clearly shown in Fig. 5. In use, the member, G, lies in contact with the upper flange, a, of the beam, 100 the plane upper end of the hanger being between the flanges, b, b, of two contiguous corrugated sheets with the hook, g, resting upon the upper face of the flange, a. A

bracket, g' , punched from the member, G , lies beneath the lower flange, a' , of the beam and an opening, g^2 , is formed in the lower end of the member, G , of each of the hangers, these openings being adapted to receive and support ceiling strips, H , to which a ceiling of any known construction may be attached. The hangers, G , G' , are supported not only by the hooks, g , resting upon the beams but also by the nails, E , E , which pass through the upper ends of the hangers as well as through the flanges, b , b , of the corrugated sheets. The sheets, B , B , are preferably of such width as to space the ceiling hangers along each beam so as to bring the ceiling strips at suitable intervals for lathing, or for the attachment of standard widths of metal ceiling sheets.

Having now described and explained my invention, what I claim as new, and desire to secure by Letters Patent, is—

1. In a flooring, the combination with suitable supporting beams and corrugated metal sheets resting upon the beams and having at their lateral meeting edges upwardly turned flanges, of suitable fastenings rigidly connecting the contiguous flanges of said sheets; substantially as shown and described.

2. In a flooring the combination with suitable supporting beams and corrugated metal sheets resting upon the beams and having at their lateral meeting edges upwardly turned integral flanges, of suitable fastenings rigidly connecting the contiguous flanges of said strips.

3. In a flooring the combination with suitable supporting beams, and corrugated metal sheets resting upon said beams and having at their lateral meeting edges upwardly turned flanges, of metal caps covering the contiguous flanges of the strips and suitable fastenings rigidly connecting said caps and flanges.

4. In a flooring, the combination with suitable supporting beams and corrugated metal sheets resting on said beams and having at their meeting edges upwardly turned flanges, of longitudinally grooved wooden flooring strips covering the contiguous flanges of the strips and having their bearings in the adjacent gutters of the corrugated sheets.

5. In a flooring, the combination with suitable supporting beams and corrugated metal

sheets resting upon the beams and having at their lateral edges upwardly turned flanges, of metal caps covering the contiguous flanges of the sheets, longitudinally grooved wooden flooring strips covering said caps and flanges and suitable fastenings rigidly connecting said flooring strips, caps and flanges.

6. In a flooring, the combination with suitable supporting beams and corrugated metal sheets resting upon said beams, of transverse drainage troughs suspended beneath the meeting ends of said sheets and adapted to receive water dripping from the sheet.

7. In a flooring, the combination with suitable supporting beams and corrugated metal sheets resting upon the beams, of transverse drainage troughs suspended beneath the meeting lines of the ends of said sheets, the ends of the gutters, of the corrugated sheets being bent downward above the drainage troughs to form drip spouts; substantially as shown and described.

8. In a flooring, the combination with suitable supporting beams and corrugated metal sheets resting upon the beams and having at their lateral edges upwardly turned flanges, of ceiling hangers having their upper ends between the contiguous flanges of said sheets and suitable fastenings connecting said flanges and hangers.

9. In a flooring the combination with suitable supporting beams and metal sheets resting upon the beams and having at their lateral meeting edges upwardly turned flanges, of suitable fastenings rigidly connecting the contiguous flanges of said sheets.

10. In a flooring the combination with suitable supporting beams and metal sheets resting upon the beams and having at their lateral meeting edges upwardly turned integral flanges, of suitable fastenings rigidly connecting the contiguous flanges of said sheets.

11. In a flooring the combination with suitable supporting beams and metal sheets resting upon said beams and having at their meeting edges upwardly turned flanges, of flooring strips rigidly fastened to the contiguous flanges of said sheets.

HERMAN B. SEELEY.
